ABSTRACT OF THE DISCLOSURE

A timepiece is provided with two turning bezels positioned concentrically, one of which at least is manually actuated and located outside the casing while the other is located inside and is rotated by the first bezel.

There are already known timepieces having two concentric turning bezels that can be manually actuated when both are positioned outside the casing and by means of a control button when they are inside the casing.

Timepieces having turning bezels have various applications, for example: drivers' watches, wherein the bezels carry then the indications of the decompression stages; universal watches, wherein the bezels bear indications of the hours in various cities on the earth; chronometers in which the bezels are graduated in hours and minutes; and speed counters in which the bezels carry a logarithmic scale showing kilometers.

The present invention has for its object a timepiece comprising two turning bezels positioned concentrically, one of which is manually actuated and is characterised by the fact that the manually actuated bezel is positioned outside the casing while the other, which is positioned inside, is rotated by the first bezel.

The accompanying drawing shows by way of example one embodiment of the invention, and the single figure shows a partial cross-section thereof.

The timepiece comprises a middle-bezel 1 against an edge of which is positioned a crystal 2 maintained by means of a tensioning ring 3 and two concentric bezels 4, 5 positioned outside and inside crystal 2 respectively.

The outer bezel 4 is maintained in a groove 6 of the middle bezel 1 by means of a polygonal annular spring 7. It has a shoulder 8 extending to the crystal and covering the middle bezel, and it has indications carried on its upper face 9. Projections 10 facilitate the manual operation of this outer bezel 4 which has teeth 11 on its lower side for meshing with a first pinion 12.

The inner bezel 5 is positioned between the tensioning ring 3 and an edge 13 of the middle bezel 1. Its lower side is also provided with teeth 14 cooperating with a second pinion 15.

The two pinions 12 and 15 are housed in a radial opening in the middle bezel and are connected by a shaft comprising two elements 16 and 17. The element connected to the pinion 12 has a groove in which is clamped a fluidtight packing 18 clamped in a sleeve 19.

Sleeve 19 has two different diameters and edge 20 which limits them also bears against joint 18. The sleeve 19 also has an outer groove in which is housed a second joint 21 cooperating with the radial opening of the mid-

2

dle bezel, said joints being for sealing said radial opening in a water-tight condition.

The assembly of the two pinions 12, 15 of sleeve 19 is maintained in the radial opening of the middle bezel by means of a closure or plug 22.

In a modification, the outer bezel 4 can be indirectly actuated by means of a button the stem of which would be integral with or would be recessed on the shaft of pinion 12.

Naturally, the angular speed of the two turning bezels can be different according to the gear ratio which is selected.

Additionally, only one of the bezels can be graduated, or on the contrary both of them; in this case, these indications can be related to one another or can be independent.

In other modifications, they could be driven by means other than gears, for example, by friction.

What is claimed is:

1. In a timepiece, a casing; a crystal fixed against said casing; and first and second turning bezels positioned concentrically, said first bezel being manually controlled and being positioned outside said timepiece casing, and said second bezel being positioned inside said casing; and rotating means passing through said casing and connecting said bezels so as to cause said second bezel to be rotated by said first bezel.

2. Timepiece according to claim 1, in which said bezels are rotatable at different angular speeds.

3. Timepiece according to claim 1, wherein said turning bezels carry markings, said markings being related to one another.

4. Timepiece according to claim 1, wherein said bezels carry markings which are independent from one another.

5. Timepiece according to claim 1, wherein said means connecting said bezels comprise gears on said bezels and two pinions positioned on the same shaft and meshing with said teeth on said bezel.

6. Timepiece according to claim 5, wherein said pinions are positioned on the shaft and said shaft is mounted on a sleeve.

7. Timepiece according to claim 1, having a button connected to said outer bezel for actuating the same.

8. Timepiece according to claim 7, wherein said button is fast on a shaft of a pinion meshing with said outer bezel.

9. Timepiece according to claim 8, having a middle, said middle having a radial opening for housing said pinions and said sleeve.
